United States Patent

Des. 240,096
Patented June 1, 1976

240,096

CHAIR OR SIMILAR ARTICLE

Christian Gunnar Haggstam, Sockenstugan, Kyrkskolan,
and Hans Tage Alfred Ehrlin, Sjostugan, Hatte, both
of S-573 00 Tranås, Sweden

Filed Sept. 10, 1973, Ser. No. 395,406

Claims priority, application Sweden Mar. 12, 1973

Term of patent 14 years

Int. Cl. D6—01

U.S. Cl. D6—47

FIG. 1.

FIG. 2.

FIG. 3

FIG. 4.

FIG. 5.

FIG. 6.

FIG. 7.

FIG. 8.

FIG. 1 is a three-quarter, front, perspective view of a chair or similar article showing our new design;

FIG. 2 is a three-quarter, rear perspective view of the chair or similar article of FIG. 1;

FIG. 3 is a three-quarter, front, perspective view of a second embodiment of a chair or similar article showing our new design;

FIG. 4 is a three-quarter, rear, perspective view of the embodiment of a chair or similar article of FIG. 3;

FIG. 5 is a bottom, perspective view of the chairs or similar articles shown in FIGS. 1-4;

FIG. 6 is a three-quarter, front, perspective view of an arrangement of two chairs or similar articles of the type shown in FIGS. 1 and 2 and showing our new design;

FIG. 7 is a rear perspective view of the arrangement of chairs or similar articles of FIG. 6;

FIG. 8 is a bottom perspective view of the arrangement of chairs or similar articles of FIG. 6.

We claim:

The ornamental design for a chair or similar article, as shown.
